VARIABLE SPEED DRIVE

James A. Jepson, Decatur, Ga., assignor to Decatur Associates, a partnership composed of James A. Jepson, Alfred Jepson, and Clyde Z. Walker, all of Decatur, Ga.

Application February 24, 1937, Serial No. 127,468

19 Claims. (Cl. 57—98)

This invention relates to an automatically controlled variable speed drive for spinning frames, cotton twister frames, cotton roving frames and the like, and more especially to a variable speed drive which is capable of gradually increasing the speed of the machine as the thread is built up upon the bobbin at a predetermined rate, and means for decreasing the rate of speed of the spinning frame at a much faster rate than it was increased after the maximum speed has been attained to cause the machine to be running substantially at the same rate of speed when the bobbin is doffed as it was when it was started.

It is a well known fact that when the yarn is being wound around bobbins on spinning frames and the like, the ring rail does not oscillate the entire length of the bobbin or quill. Instead, the ring rail oscillates or traverses approximately one-fourth the length of the bobbin at the beginning, as as the thread is built up upon the bobbin to form the appearance of an inverted cone at the lower end thereof, the ring rail gradually rises relative to the bobbin but at the same time maintains the same length stroke of oscillation.

Due to the fact that the balloon of yarn, when it first starts from the bobbin, is much greater than it is when the bobbin is doffed, it naturally follows that the air resistance to this yarn will be much greater; consequently, it is necessary that the rate of speed at the beginning of the bobbin be much slower than it will be when the ring rail rises towards the top of the bobbin where there is less balloonage and windage of the strand.

Furthermore, at the beginning of the deposit of yarn on the bobbin, the size of the cone is small and the angularity of the yarn between the bobbin and the traveller is great, resulting in an additional friction which is reduced after the bobbin has been built up to a larger diameter.

It is therefore, seen that it is very desirable that means be provided for gradually increasing the speed of spinning frames and the like, as the ring rail moves upwardly in its reciprocatory movement, and as the size of the bobbin builds up since the friction and air resistance to the yarn is considerably decreased at this time.

It is therefore, an object of this invention to provide a variable speed drive for spinning frames and the like comprising means for gradually increasing the speed of the machine as yarn is being wound into the bobbin until the speed has attained the desired maximum speed and means for maintaining this maximum speed for a predetermined time, and further means for de-

ing the speed of the spinning frame at a much greater rate of speed than it was increased until the speed has been reduced to starting speed. When the starting speed has been reached, the bobbins are ready to be doffed and when additional quills are placed on the spindles the machine stands adjusted to the proper starting speed without the necessity of any other manual operation. 5

It is a further object of this invention to provide a variable speed drive for a machine, such as spinning frames and the like, comprising an expansion pulley mounted on the drive shaft of a machine which is driven by a suitable motor by means of a belt, and having means operated by the oscillation of the ring rail of the spinning frame for bodily moving said motor relative to said expansion pulley and at the same time moving the disks on said expansion pulleys relative to each other to compensate for the movement of said motor thereby opening the disks in perfect synchronization with the movement of the motor. This allows the belt to change position in the disks to increase or decrease the R. P. M. of the driven shaft and at the same time keep the belt in perfect alignment and at an even tension. The alignment is maintained since both disks spread exactly the same amount relative to the center line or the belt, and the even tension is maintained since positive means are provided for expanding or contracting the disks according to the distance that the motor is removed from the shaft. 20 25 30

It is a further object of this invention to provide in variable speed drive for spinning frames of the class described, an automatic clutch for increasing and decreasing the speed of the spinning frame at a predetermined rate with manual means for disengaging said automatic clutch while the spinning frame is still in motion and having means for re-setting the spinning frame at a different speed. This is very often desirable in many instances such as when false roving makes it impossible to operate the frame at a predetermined high speed. By means of the hand clutch control it is possible to allow the speed to reach any point between high and low speed and then turn the same back to any intermediate point. Also, when atmospheric conditions cause the work to run bad in the mills and slower or higher speed is found to be advantageous during such bad periods. The hand clutch is used to turn the frame back to a slower speed and thereafter the speed gradually increases again. If it were not for the hand clutch, it would be 40 45 50 55

necessary to disturb the setting of the automatic clutch trips governing the main control unit. These trips have practically permanent settings for different types of spinning frames, therefore, it is desirable to disturb these as little as possible. There are other instances in which the hand control lever is used to an advantage, but the above cases are merely cited to illustrate some of the important functions which it performs, as the other functions of the hand control will appear in the detailed description hereinafter following.

In variable speed drives, the rate of speed of the driven machine is effected by having a pair of beveled members pressed towards each other by a compression spring. When increased pressure is applied to the belt it is pressed more deeply in between the beveled members to decrease the rate of speed of the machine. The spring pressure changes, due to temperature, and also on account of the pressure on the edges of the belt increasing as greater tension is applied to the belt. This apparatus embodies positively driven means for moving both beveled disks towards and away from each other and at the same time moving the motor to cause the tautness of the belt to remain practically constant at all times.

Some of the objects of the invention having been stated, other objects will appear as the description proceeds when taken in connection with the accompanying drawings, in which:

Figure 1 is an end elevation of my invention which is located at the end of a spinning frame;

Figure 1A is an elevation of a crank which is used for manually positioning the motor for a given speed;

Figure 2 is a plan view looking down on Figure 1 showing portions of a spinning frame in section;

Figure 3 is a sectional plan view taken along line 3-3 in Figure 1;

Figure 4 is an elevation of the invention looking at the left-hand side of Figure 1 showing a portion of a spinning frame associated therewith;

Figure 5 is an enlarged sectional detail view taken along the line 5-5 in Figure 4, and showing the parts in a slightly different position;

Figure 6 is a sectional elevation taken along line 6-6 in Figure 2;

Figure 7 is an enlarged sectional view taken along line 7-7 in Figure 6;

Figure 8 is a vertical, sectional view taken along line 8-8 in Figure 1;

Figure 9 is a vertical, sectional view taken along the line 9-9 in Figure 1;

Figure 10 is a sectional, detail view taken along line 10-10 in Figure 8;

Figure 11 is a sectional detail view taken along the line 11-11 in Figure 2;

Figure 12 is a sectional view taken along line 12-12 in Figure 11.

Referring more specifically to the drawings, the numeral 10 denotes an end frame of a suitable textile machine such as a spinning frame, which has longitudinally disposed bottom rails 11, bolster rail, 12, spinning rails 13, and thread guide rails 14. Each bolster rail 12 has secured therein suitable bolsters 15 in which rotate spindles 16, each of said spindles having a bobbin 17 removably mounted thereon. A strand of yarn 18 is drawn downwardly from the drafting rolls, not shown, through an eyelet 14a, and then to the traveler 19 from whence it is deposited upon the bobbin 17.

As previously stated, it is necessary that the speed of the bobbin be relatively slow when the 75 yarn is first started thereon because the windage

of the yarn is at its maximum at this point and also the tension between the traveler and the bobbin is its greatest. Consequently, it is necessary to have a slow starting speed when the yarn is started at point 20, Figure 5. It is then very desirable to gradually increase the speed until the point 21 is reached at which time the machine is at its maximum speed. This speed is maintained until a point, such as 22, is reached, and at this time it is desirable to quickly reduce the rate of speed to the starting speed by the time point 23 is reached. When the point 23 is reached, the packages of yarn are completed and are ready to be doffed.

It is also quite evident that it is desirable to maintain the maximum speed as long as possible between the points 21 and 22 so that the maximum production can be obtained. In order to do this, it is necessary to shorten the interval of time consumed in winding the yarn between the points 22 and 23.

In other words, the objective is to reduce the speed at a much greater rate than it was increased. This can very well be accomplished since the windage of the yarn at point 22 has been materially decreased and also the friction between the traveler 19 and the package of yarn has also been decreased due to the increased diameter of the bobbin. The ring rail traverses approximately the lower fourth portion of the bobbin at the beginning and maintains the same length of traverse throughout the winding of the yarn but it gradually moves upwardly towards the top of the finished bobbin by increments until the final traverse takes place between points 23 and 23a. The means for causing the rail to move upwardly in this manner is a conventional builder motion, and therefore, a description will not be made.

The ring rail 13 has secured thereto a vertically disposed plunger or rod 21 which is slidably mounted in bottom rail 11 and bolster rail 12. The lower end of this plunger is secured to the free end of lever 28, said lever being fixedly secured on the end of ring rail cross shaft 29. Also, fixedly secured to this cross shaft 29 is a vertically disposed lever 30, the upper end of which has pivotally secured thereto a horizontally disposed link 31. The other end of link 31 is pivoted as at 32 to a bolt 33, said bolt 33 being adjustably mounted in slot 34, (Figure 1), which is provided in the lower end of oscillating clutch lever 35. This lever is pivoted intermediate its ends on shafts 38 and 39 at their junction points, which shafts are rotatably mounted in suitable bearings disposed on the tops of boxes 40 and 41 respectively.

It will be noted by referring to Figures 1 and 3 that shafts 38 and 39 are not fixedly connected to each other but relative movement is permitted between the two since their only connection is a loose male and female joint, (Figure 3). The upper end of lever 35 (Figures 8, 9 and 10), is penetrated by bolt 42, each end of said bolt having pivotally secured thereon suitable pawls for engaging suitable ratchet wheels which will be presently described.

The arm 35 is caused to oscillate during the winding of yarn 18 upon the bobbin 17 due to the fact that the ring rail 13 traverses the bobbin during that time. This vertical up and down movement, of course, is imparted to arm 35 through links 27 and 31 which have been previously described.

A pawl 43 is pivotally supported on one end of bolt 42 and is adapted, at times, to engage a 75

suitable ratchet wheel 44 which is loosely mounted around shaft 38. Pawl 43 is normally held in one of two positions by means of a plunger 45, (Figure 10), which is slidably mounted in a bore disposed in the hub portion of this pawl. Plunger 45 has a restricted portion 46 around which a coiled compression spring 47 is mounted. This compression spring normally presses the plunger 45 against the side of the upper portion of the T-shaped lever 35 and into suitable cavities or 10 detents 48 and 48a in lever 35. When the pawl is in an engaged position, as shown in Figure 8, plunger 45 is disposed in detent 48 such as shown also in Figure 10, whereas, if it is desired to move the pawl to a disengaged position, it is rotated in a counter-clockwise manner in Figure 8, to cause the pawl to engage the detent 48a which is placed at a predetermined distance from detent 48, Figure 8.

The hub of pawl 43 also has integral therewith an upwardly extending projection 49 which projection is adapted to be contacted by stop 50 when the ring rail is moved downwardly to its lowermost position. Of course, when this projection 49 contacts projection 50 the pointed portion of the pawl will be caused to engage the ratchet wheel 44. It might be further stated that when the packages of yarn are doffed, the ring rail 13 is pushed downwardly to its lowermost position, which position is lower than the initial traverse position of this ring rail. This is done so that the loose ends will be tied around the bottom of the spindles 16. After the pawl 43 is placed in engaging position by the stop 50, the spinning frame is again placed in operation and the yarn is started to be wound around the lowermost portion of the bobbins 17.

As previously stated the vertical oscillation of ring rail 13 will cause a corresponding oscillation of the lever 35 and the pawl 43. The oscillation of lever 35 will therefore, cause ratchet wheel 44 to be rotated intermittently in a clockwise manner, (Figure 8) which, in turn, will rotate the shaft 38, that is, if the clutch face 44a is engaged with the clutch face 55a of clutch member 55.

Clutch 55 is slidably mounted on shaft 38 by means of keys 56 and this member is also normally pressed toward ratchet wheel 44 by means of a compression spring 57 so that the clutch faces 44a and 55a will tend to engage each other.

The lower end of a forked lever 58 normally engages left hand surface of the rim of clutch member 55 (Figure 1) when the clutch faces 44a and 55a are desired to be disengaged. This member is pivotally secured as at 59 and also has loosely mounted in the upper end thereof a horizontally disposed sliding rod 60 by any suitable means such as nuts 61 disposed on opposed sides of the upper end thereof. The rod 60 is slidably mounted in downwardly projecting members 62 and 63 which extend downwardly from the base member 64 upon which the motor 65 is mounted. The other end of rod 60 has a collar 66 adjustably secured thereto which is contacted by the downwardly extending projection 63 when the motor moves to the left in Figure 1 and engages the same.

It is quite evident that when the collar 66 is engaged by projection 63 that the forked lever 58 will be rotated in a counter-clockwise manner in Figure 1 to cause the clutch face 55a to become disengaged from clutch face 44a and thereby render the rotation of the ratchet 44 ineffective so far as its control of the speed of the machine.

is concerned. However, it would be stated that the collar 66 is not engaged by the projection 63 until the motor has been moved to the left so as to cause a maximum speed of the machine to be attained. After a maximum speed has been reached, the motor will remain in a stationary position which is somewhat to the left of its position shown in Figure 1 for a predetermined time, after which, other means which will be later described will be brought into operation to cause the motor to again move to the right and consequently reduce the speed.

Motor 65 is moved to the left when the yarn is started on bobbins 17 by means of a suitable pinion 70 which is secured to the end of shaft 38, said pinion 70 meshing with a larger pinion 71 loosely mounted on shaft 72 but it has a clutch face 71a which normally engages a clutch face 73a of clutch 73. Clutch 73 is keyed to the shaft 72 by means of key 74 but is adapted to have longitudinal sliding movement thereon. A suitable compression spring 75 (Figure 1) normally forces the clutch faces 71a and 73a into an engaged position and when the parts are in the engaged position as shown in Figure 1, the rotation 20 of the ratchet 44 will impart rotation to the shaft 72 through pinions 70 and 71. The shaft 72 is rotatably mounted in bearings 79 and 80 which are secured to top frame work 81, which rests upon base frame 82 which in turn is supported by a plurality of short pipes or columns such as 83.

Rod 72 has a threaded portion thereon upon which is threadedly mounted block 84 which extends upwardly and is confined between the downwardly projecting members 62 and 63. 35 Therefore, when the ratchet wheel 44 causes shaft 72 to rotate so that the top portion thereof is moved toward the observer in Figure 1, the block 84 will be forced to the left and consequently the motor 65 and its base 64 will be also moved to the left.

By referring to Figure 4, it is seen more clearly how the slide 64, upon which motor 65 is mounted, operates in the top of the framework. The slide 64 has V-shaped edges which are adapted to fit in coinciding grooves which are disposed in table top 88, this top is fixedly secured to the top of framework 81.

The motor 65 has a suitable shaft 89 extending therefrom upon which is secured a V-pulley 90. 50 Mounted upon this pulley is a transmission belt 91 which belt extends downwardly and is also mounted upon an expansion V-pulley 92, said expansion pulley comprising disks 93 and 94 which are adapted to be moved toward and away from each other to cause the belt 91 to rotate on the desired circumference, and consequently, produce the desired speed of rotation of a shaft 96.

It can be readily seen, by referring to Figure 1, that as the motor 65 progresses to the left, the transmission belt 91 will be caused to rotate upon a smaller diameter between disks 93 and 94 and therefore the shaft 96 will be caused to rotate at a higher speed. In other words, the R. P. M.'s of shaft 96 will gradually be increased as the motor 65 moves to the left causing the belt to rotate upon a smaller circumference between the previously described disks.

The disks 93 and 94 are slidably keyed to a sleeve 97 by any suitable means such as keys 97a, but these disks are adapted to have longitudinal sliding movement upon this sleeve. The sleeve 97 is fixedly secured to shaft 96 by any suitable means such as a pin 98. Rotatably secured around the hub of disks 93 and 94 are collars 100 75

and 101 respectively. The proximate faces of these collars are adapted to contact suitable thrust bearings 103 and 104 for normally forcing or holding the disks 93 and 94 in their proper position. Instead of providing the conventional spring pressed disks which are operated by the tension of the belts for causing the same to expand or to contract and consequently produce the desired change in the speed, I have provided 10 positive means whereby the disks 93 and 94 will be spread or closed as the motor 65 moves to the left or to the right respectively in Figure 1. By providing this positive means it is evident that the tension upon the belt will remain practically constant as the motor moves towards and away 15 from the expansion V-pulley. At the same time the lateral pressure upon the thrust bearings 103 and 104 will also be kept practically constant.

In order to provide this positive means I have 20 secured on opposed sides of the hub 100 suitable rollers 105, which rollers are engaged by the lowermost forked ends of levers 106. These levers are pivoted intermediate their ends as at 107 to opposed sides of interiorally threaded collar 108 which is threadably mounted upon shaft 109. The upper ends of the levers 106 are also forked and are adapted to engage rollers 110 which are secured on opposed sides of an interiorally threaded collar 111. This collar is likewise 25 threadably secured around a suitable shaft 112.

Likewise, hub 101 has rollers 114 secured on opposed sides thereof which are engaged by the lower forked ends of levers 115, said levers 115 being pivotally secured as at 116 to an interiorally threaded collar 117 which is threadably mounted on shaft 109. The upper end of these levers 115 are forked and are adapted to engage suitable rollers 118 which are disposed on the upper and lower sides of interiorally threaded collar 119 threadably mounted on shaft 112. The shaft 112 is rotatably mounted in bearings 120 and 121. This shaft has a beveled gear 123 secured on rod or shaft 72. When the yarn is started on bobbin 17 the shaft 72 is caused to rotate with the top portion thereof moving toward the observer in Figure 1 which causes the motor 65 to move to the left. At the same time the beveled gears 123 and 122 will cause the shaft 112 to rotate in a clockwise manner in Figures 1 and 2, which, in turn, will cause the collars 111 and 119 to move toward each other and thereby cause the disks 93 and 94 to spread. It is therefore seen that the spreading of the disks is synchronized with the movement of the motor 65 toward and away from the shaft 96 thereby causing the transmission belt 91 to have an even tension thereon at all times.

It is further seen that by providing means for expanding or moving laterally both of the disks 93 and 94 simultaneously, the belt 91 can be kept in alignment at all times, whereas, if only one disk moved laterally then the belt 91 would become warped or twisted unless means were provided for the corresponding lateral movement of the fixed pulley 90 which is disposed thereabove.

The ends of shaft 109 are rotatably secured in bearings 126 and 127. The end of rod 109 which rotates in bearing 127 has a collar 129 fixedly secured thereon which has a bore therein and said bore is slidably mounted on a plunger 130 (Figure 12). This plunger has a restricted portion 131 around which mounted a coiled compression spring 132. This spring normally presses the plunger 130 into suitable spaced detents 133 which

are disposed in the face of bearing 127 which is adjacent to collar 129. The intermediate portion of the rod 109 has a squared portion 109a which may be engaged by a suitable wrench to turn this rod. Since the ends of the rod have right and left hand threads disposed thereon it is evident that when rod 109 is turned the collars 108 and 117 will be moved, either toward each other or away from each other depending upon the direction of rotation imparted to the rod. The function of the plunger 130 and detents 133 is to hold the rod 109 in the position to which it has been turned. The rod 101 is turned when a finer adjustment is desired relative to the spacing of the disks 93 and 94 as for example, when it is desired to tighten the belt. When this adjustment has once been made it is rarely ever necessary to change the same unless the belt becomes worn or too loose.

In order to prevent rotative movement of the 20 collars 111 and 119 and also collars 108 and 117 suitable L-shaped members 135 and 136 are provided (Figures 2 and 6) each of which have one leg thereof projecting substantially parallel to the upper members 115 and 106 for a substantial 25 distance and then these members are turned downwardly at an angle of 90 degrees so that the lower end thereof will stop short of the lower members which are disposed directly below the said upper members.

As previously stated, the arm 35, in Figure 3, oscillates back and forth about its pivot point from the time the package is first started on bobbin 18 until it is completed; however, pawl 43 is only allowed to engage the ratchet teeth 35 in ratchet 44 to increase the speed of the spinning frame until the point 21 on the package of yarn in Figure 5, is reached. At this time the maximum speed has been obtained and it is desired to operate at this speed until the point 22 is reached. When the point 21 is reached the pawl 43 is thrown into a disengaged position since the projection 49 will be oscillated at this time far enough to the right in Figure 3 to cause it to be engaged by the lower end of pivoted dog 138. When the projection 49 engages this dog the pawl 43 will be thrown to dotted line position and although member 35 will continue to oscillate, the ratchet 44 will not be moved and consequently, the motor 65 will not be forced any further to the left in Figure 1. This means that the maximum speed will continue until a predetermined point such as 22, Figure 5, is reached in the winding of the package of yarn. It will be noted that the stop 50 is adjustably mounted 50 in a slot 140 of arcuate member 141. Likewise, dog 138 and its associated bracket 142 is adjustably secured in the slot 140 and when these members 50 and 142 have been once set to accommodate a special type of spinning frame it 60 is rarely ever necessary to disturb these settings. In other words, the slot 140 is provided so that these stops may be set to accommodate various types of frames upon which this apparatus is used and this adjustment is usually made when 65 the machinery is installed in the mill. The bracket 142 has a tension spring 144 secured thereto, the other end of said spring being adapted to be connected to the upper end of dog 138. Thus, it is seen that this dog may be rotated 70 a limited amount in a clockwise manner in Figure 3 by the projection 49 when this projection oscillates to the right of the lower end of this dog. But it should be noted that before the speed has been increased sufficiently to cause the pro-

30

35

40

55

60

65

70

75

jection 49 to oscillate past the lower end of dog 138 the pawl 48 is still in bold line position and operating the ratchet 44. When this projection 49 contacts the lower end of this dog pawl 43 will be rotated in a counterclockwise manner to cause the same to assume the dotted line position. In other words, when this rotation of pawl 43 takes place the plunger 45 is moved out of detent 48 and into detent 48a where it is held in an inoperative position.

By referring to Figures 9 and 10, it will be noted that the other end of pin 42 has pivotally secured thereon another pawl 146. This pawl is similar in all respects to the pawl 43 previously described and is held in engaged and disengaged position by means of detents 48 and 48a and plunger 45 which has been previously described in connection with pawl 43. This pawl has a projection 147 extending upwardly therefrom which is adapted to contact the lower end of pivoted dog 149 when the point 22 is reached in Figure 5 in the winding of the bobbin. When this projection is contacted the pawl 146 is thrown to dotted line or engaged position with ratchet 150 after which the ratchet will be caused to intermittently rotate in a counterclockwise manner in Figure 9.

Dog 149 is similar in all respects to dog 138 and has a suitable tension spring 151 secured thereto for normally holding the dog in the position shown in Figure 9. Likewise, the bracket 152, in which the pivoted dog 149 is secured, is adjustably mounted in a suitable slot 153 which slot is cut in semi-circular ring member 154. It should be noted that the dog 149 is located farther to the right relative to the shafts 38 and 39 than the dog 138, so that when the maximum speed has been attained the dog 138 will throw the pawl 43 to disengaged position and during the operation under maximum speed both pawls 43 and 146 will be disengaged. After the ring rail 13 has moved high enough to cause the oscillation of the upper end of lever 35 to cause the projection 147 to contact dog 149, then the pawl 146 will be rotated so that it will engage the ratchet 150 and thereby operate means for gradually decreasing the speed of the spinning frame which will be hereinafter described.

The ratchet wheel 150 has a clutch face 150a integral therewith which is adapted to mesh with a second clutch face 155a of clutch 155. This clutch is secured to shaft 39 by means of keys 156 but is allowed to have longitudinal sliding movement on said shaft. A compression spring 157 normally forces the clutch 155 to the right in Figures 1 and 3, to cause clutch faces 155a and 150a to become engaged.

A forked lever 158 has the lower end thereof astride the shaft 39 and normally engages the rim of clutch 155, when the clutch faces 150a and 155a are in a disengaged position. This lever 158 is pivoted intermediate its ends as at 159 and has secured in the upper end thereof a horizontally disposed sliding rod 160 by means of nuts 161, the left hand end of said rod 160 being adapted to be engaged by the downstanding projection 62 of the motor slide face 64 when the motor is positioned so as to produce the slowest speed of shaft 96, that is, when the motor is positioned in its extreme right-hand position in Figure 1. However, when the arm 35 is oscillating far enough to the right in Figure 9, to cause the projection 147 to be engaged by dog 149, the motor 65 will be positioned in its extreme left-hand position so that the downstand-

ing projection 63 will be contacting the collar 66 in Figure 1.

The primary function of pawl 146 and ratchet 150 is to move the motor 65 to the right so that it will occupy the position shown in Figure 1 as quickly as possible after the yarn has been wound to point 22 on the package of yarn, in Figure 5.

After the pawl 146 has been moved to dotted line position, so that it will engage ratchet 160, each oscillation of ring rail 13 and arm 35 will rotate the ratchet 150 and the shaft 39 in a counter-clockwise manner and this motion will be transmitted to pinion 165 which is fixedly secured on the end of shaft 39 (Figure 9). Meshing with this pinion is another pinion 166 which is rotatably mounted on shaft 72. Pinion 166 has integral therewith a clutch face 166a. This clutch face meshes with another clutch face 168a of clutch hub 168, which is secured to shaft 72 by means of suitable key ways 169. This hub is adapted to have longitudinal sliding movement relative to the shaft 72 and is normally forced into engagement with the clutch hub 168 by means of compression spring 170.

In other words, when the clutch face 155a and 150a are in engaged position the rotation of ratchet 150 and shaft 39 will cause the shaft 72 to rotate in such a manner so as to move the motor 65 to the right. Furthermore, since the pinion 166 is considerably larger than pinion 165, it is seen that this movement of the motor 65 to the right will be faster than its movement was to the left which was produced by pinions 70 and 71.

There are many cases in which it is necessary to change the speed of the spinning frame before the operation is completed; therefore means have been provided whereby the control mechanism which is operated by pawls 43 and 146 along with ratchets 44 and 150 respectively, and their associated parts may be disengaged from the other portions of the machine while the machine is still running and to enable one to employ means whereby the motor may be positioned so that the desired speed will be effected.

In order to provide this disengaging means, a forked lever 175 has been provided with its lower end astride the hub of clutch member 168 and having the forked ends normally engaging the flange of said hub. Forked lever 175 is pivoted as at 176 to downwardly extending bracket 177 (Figure 1). The upper end of the forked lever 175 is pivoted as at 178 to a horizontally disposed link 179 which extends laterally of the machine in Figure 1 and has its other end pivoted as at 180 to the upper end of forked lever 181. Forked lever 181 is pivoted intermediate its ends as at 182 to the bracket 177. The lower forked end of the lever 181 rests astride the hub of member 13 and is normally adapted to contact the flange of said member. In order to move the link 179 to the left in Figure 1, and thereby cause the clutch faces 166a and 168a to become disengaged as well as to cause the clutches 11a and 13a to become disengaged a lever 185 is pivoted as at 186. This lever is operated manually to accomplish this result. When the hand lever 185 is rotated in a clockwise manner, in Figure 1, the above-described clutches will be disengaged and the parts in the lower portion of the machine associated with pawls 43 and 146 will be disengaged from the shaft 72, after which it is only necessary for the operator to take the hand crank 188 as shown in Figure 1, and place the squared cavity 189 over the squared end 72a of shaft 72

and turn the motor 65 to the desired position so that the machine will run at the desired speed.

It is desirable to use this hand clutch in cases such as where doffing of the bobbin is effected before it is filled, and before the automatic control has returned the spinning frame to the starting speed. Also, when the atmospheric conditions causes the work to run bad in the mill and a slower or higher speed is found to be advantageous during such bad period, or it may be necessary to use the clutch when faulty roving makes it impossible to operate the spinning frame at a predetermined speed and as a consequence, the ends begin to break down in increasing numbers.

When the yarn numbers are changed, and different minimum and maximum speeds are required, it is not necessary to disturb control which is associated with pawls 43 and 146. Instead, the position of collar 66 on rod 68 may be changed, or the position of the rod of rod 160 may be changed. These changes will vary the time at which clutch faces 44a and 55a or clutch faces 150a and 155a will be thrown to disengaged position. If it were not for the hand clutch it would be necessary to disturb the settings, that is, the position of the stops 50, 138, 149, or 149a as shown in Figures 8 and 9. These stops determine the time at which the pawls 43 and 146 are held in engaged position with their respective ratchet wheels.

It will be observed that the speed at which the spindles 16 and bobbins 17 rotate is in direct proportion to the speed of the shaft 96. This is true, due to the fact that the drum 191 is fixedly secured on the shaft 96 and upon this drum are mounted suitable belts 192 which, in turn, are mounted on spindle whorls 193 for driving the spindles 17.

It is therefore, seen that I have provided positive means for expanding the pulley disks to the desired position to correspond with the remoteness of the position which the motor occupies relative to said pulleys, thereby causing the grip upon the ends 91a and 91b of the links of belt 91 to remain constant regardless of what circumference within the disks 93 and 94 on which the belt may be running.

I have also provided means for gradually increasing the speed of rotation at the beginning of the bobbin in increments and means for maintaining a maximum speed for a predetermined time and then means for reducing the speed back to the initial speed at a greater rate than the said speed was increased. And finally means have been provided for changing the speed of spinning frames while in operation before the operation is completed by the use of the above-described hand clutch mechanism.

In the drawings and specification there has been set forth a preferred embodiment of the invention, and although specific terms are employed, they are used in a generic and descriptive sense only, and not for purposes of limitation, the scope of the invention being set forth in the appended claims:

I claim:

1. A variable drive for spinning frames and the like comprising a motor having a shaft, a V-pulley fixedly mounted on said shaft, a main drive shaft for the spinning frame, an expansion V-pulley having its proximate faces beveled and said faces being movable towards and away from each other on said drive shaft, means driven by the spinning frame for moving the motor relative to

the expansion V-pulley and other means also driven by the machine for moving the two faces of said expansion pulley away from each other as the motor moves away from the expansion pulley and for moving the faces of the expansion pulley towards each other as the motor moves towards the expansion pulley, and a belt mounted on said pulleys.

2. In a machine having a main drive shaft and a motor having a shaft for driving the machine, said motor shaft having a V-pulley thereon, an expansion V-pulley being split transversely of its longitudinal axis and having its two portions slidably keyed on the drive shaft, a belt mounted on the two pulleys, means driven by the machine for moving the motor towards and away from the expansion pulley and other means for moving the two portions of said expansion pulley away from and towards each other in proportion to the movement of the motor to thereby maintain the desired tautness in the belt.

3. In a machine having a main drive shaft and a motor having a shaft for driving the machine, said motor shaft having a V-pulley thereon, an expansion V-pulley being split transversely of its longitudinal axis and having its two portions slidably keyed on the drive shaft, a belt mounted on the two pulleys, means driven by the machine for moving the motor towards and away from the expansion pulley and other means for moving the two portions of said expansion pulley away from and towards each other in proportion to the movement of the motor to thereby maintain the desired tautness in the belt and manually operable means for adjusting the position of the motor with relation to the expansion pulley.

4. In a fiber preparation machine having a main drive shaft and a motor provided with a shaft and also having a vertically reciprocating ring rail, a V-pulley fixed on said motor shaft, an expansion V-pulley having its two parts slidably keyed on said main drive shaft to rotate with said shaft, a belt mounted on said V-pulleys, means driven by the ring rail for moving said motor towards and away from main drive shaft, other means driven by the ring rail for moving the two portions of the expansion V-pulley relative to each other in proportion to the travel of the motor to thereby maintain a uniform tautness in said belt.

5. In a fiber preparation machine having a main drive shaft and a motor provided with a shaft and also having a vertically reciprocating ring rail, a V-pulley fixed on said motor shaft, an expansion V-pulley having its two parts slidably keyed on said main drive shaft to rotate with said shaft, a belt mounted on said V-pulleys, means driven by the ring rail for moving said motor towards and away from main drive shaft, other means driven by the ring rail for moving the two portions of the expansion V-pulley relative to each other in proportion to the travel of the motor to thereby maintain a uniform tautness in said belt, automatic means for rendering the means for moving the motor with relation to the drive shaft inoperative when the motor has reached a predetermined point and rendering operative the means for moving the motor in the other direction.

6. Variable drive mechanism comprising a driven shaft and a driving shaft, a V-pulley mounted on the driving shaft, an expansion V-pulley mounted for sliding movement on the driven shaft and being keyed on the driven shaft to drive the same, a belt mounted on the two

5 pulleys, means for moving the motor relative to the driven shaft, means for moving the parts of the expansion V-pulley away from each other as the motor moves in one direction, other means for moving the motor in a reverse direction from the said first motor moving means, means for rendering one of said motor moving means inoperable and rendering the other operable at predetermined points in the travel of the motor, one 10 of said motor moving means being geared to move the motor at a more rapid rate than the other motor moving means.

15 7. In a machine for spinning fibers, apparatus for rotating the bobbins in said machine at a low and gradually increasing initial rate and a high rate during the formation of the yarn on the bobbin and a rapidly decreasing finishing rate, comprising a driven shaft and a drive shaft, a V-pulley mounted on the drive shaft, an expansion V-pulley having its two parts keyed on 20 said driven shaft for movement towards and away from each other, a belt mounted on said V-pulleys, means driven by the machine for moving the parts of said expansion pulley away from each other and moving said motor away from 25 said expansion pulley at a slow and gradually increasing rate, automatic means for rendering all of said moving means inoperative for a predetermined time, other means driven by the machine for moving said portions of said expansion pulley towards each other and moving said motor towards 30 said expansion pulley at a rapidly decreasing rate and automatic means for rendering said other means inoperative when the motor has returned to another predetermined point.

35 8. In a fiber preparation machine having a ring rail and a main shaft, a motor for driving the main shaft, said motor having a motor shaft provided with a V-pulley thereon, said main shaft having an expansion V-pulley thereon having its 40 beveled faces movable towards and away from each other, a belt mounted on said pulleys, the parts of said expansion pulley being keyed on said main shaft to drive the main shaft but being 45 slidable longitudinally on the main shaft, a motor mounted for sliding movement on a horizontally disposed table, a threaded shaft having threaded connection with the motor, a train of gears driven by the ring rail for driving said threaded shaft in one direction for moving the motor along said 50 table, a second train of gears for driving said threaded shaft in a reverse direction for moving the motor in a reverse direction along said table, means automatically operable upon the motor 55 reaching a predetermined position on said table for rendering the first train of gears inoperative and rendering the other train of gears operable, the second train of gears being of a ratio to move the motor appreciably faster along the table than the first train of gears moved it to said predetermined point.

60 9. Apparatus for driving a spinning frame having a ring rail for depositing yarn onto bobbins and comprising a motor provided with a motor shaft and a V-pulley mounted on the motor shaft, a driven shaft for the machine having an expansion V-pulley thereon comprising two parts mounted on said driven shaft for movement towards and away from each other, a belt mounted 65 on said pulleys, means for mounting said motor for horizontal movement so that the weight of the motor will offer the same resistance to moving it in either direction, a threaded shaft engaging the motor, a lever oscillated by the ring rail, means for moving the portions of the expansion 70

V-pulley towards and away from each other on the driven shaft, means operable by the oscillating lever upon the beginning of winding of yarns onto bobbins for moving said parts of said expansion pulley away from each other and also 5 moving the motor away from the driven shaft, means for rendering the oscillating lever inoperative to drive said shaft and said parts of said expansion pulley when a predetermined amount of yarn has been wound onto the bobbins, other 10 means for driving the threaded shaft in a reverse direction, means automatically operable when another predetermined amount of yarn has been wound onto the bobbins for rendering operable said other means for driving the threaded shaft and moving said parts of said expansion pulley to move the motor nearer the driven shaft and to move the parts of the expansion pulley towards each other at a greater rate of travel 15 than they were moved away from each other. 20

10. In a spinning frame having a ring rail for depositing yarn onto bobbins and said ring rail being vertically movable and vertically reciprocable, a motor having a shaft, a drive shaft for the spinning frame, a V-pulley mounted on the motor 25 shaft, an expansion V-pulley mounted on said drive shaft and being keyed for sliding movement longitudinally of the drive shaft, said expansion pulley being in two parts whereby the beveled faces of the expansion pulley can be moved relative to each other, a belt mounted on said pulleys, means driven by the ring rail for moving the motor and at the same time positively moving the two parts of the expansion pulley relative to each other so that the belt will remain taut as 30 35 the speed of the spinning frame is changed.

11. A spinning frame having bobbins and a ring rail which is vertically reciprocable and vertically movable to deposit yarn onto the bobbins, a motor provided with a motor shaft having a 40 V-pulley thereon, a drive shaft for the machine having an expansion V-pulley thereon, means controlled by the ring rail of the spinning frame for moving the parts of the expansion pulley relative to each other and other means for moving 45 the position of the motor relative to the expansion pulley to thereby vary the rate of rotation of the bobbins and at the same time maintain a constant desired tautness in the belt.

12. Apparatus for driving a fiber preparation 50 machine having a ring rail provided with means for vertically reciprocating the ring rail and gradually raising the ring rail, comprising a drive shaft having a V-pulley thereon and a driven shaft having an expansion V-pulley mounted for 55 sliding movement thereon, apparatus for moving the two portions of said expansion pulley relative to each other on said driven shaft, a belt mounted on said pulleys, a threaded shaft for moving the drive shaft with relation to the driven 60 shaft, means operable by the reciprocation of the ring rail for driving the threaded shaft to move the motor, means automatically operable upon the drive shaft reaching a predetermined point for disconnecting the means driven by the ring 65 rail from the threaded shaft, means for driving the threaded shaft in a reverse direction, means operable upon the ring rail reaching a predetermined elevation for connecting the last named means to the threaded shaft for returning the 70 drive shaft towards the driven shaft and moving the portions of the expansion pulley towards each other to gradually decrease the rate of rotation of the bobbins in the machine.

13. Apparatus for driving a spinning frame and 75

- the like so that the yarn will be wound onto the bobbins at a low and gradually increasing rate of speed at the beginning of the winding and the body of the bobbin will be wound at a high rate of speed and during the completion of the winding of the bobbin, the yarn will be wound at a decreasing rate which is more rapid than the increasing rate at the beginning of winding, comprising a drive shaft having a V-pulley thereon, 5 a driven shaft having a split V-pulley slidably keyed on the driven shaft so that the parts of the split V-pulley may be moved towards and away from each other, a belt mounted on said pulleys, means driven by the machine for moving the parts of said split pulley away from each other and moving the motor with relation to the split pulley to keep the belt taut, other means for stopping the travel of the motor when the portions of the split pulley have been moved a predetermined distance from each other, and mechanism automatically operable after a predetermined amount of yarn has been wound onto the bobbin for moving the portions of the split pulley towards each other and moving the motor 10 nearer the split pulley at a more rapid rate than the portions of the pulley were moved away from each other at the start of the bobbin.
14. Driving means for spinning frames having bobbins and a vertically reciprocable and vertically movable ring rail, a motor having a motor shaft provided with a V-pulley, a table, means for mounting the motor for horizontal movement on said table, a drive shaft for the spinning frame, an expansion V-pulley mounted in said 15 drive shaft for sliding movement of its two parts relative to each other, a belt on said pulleys, means driven by the movements of the ring rail for moving the motor horizontally on said table and also for moving the parts of said expansion pulley relative to each other proportional to the movement imparted to the motor so that the belt will retain a predetermined tautness regardless of the relative positions of the motor with relation to the expansion pulley.
15. A variable drive for spinning frames and the like comprising a motor having a shaft, a main drive shaft for the spinning frame, a V-pulley fixedly mounted on one of the shafts and an expansion V-pulley keyed on the other shaft 20 for sliding movement longitudinally thereof, means driven by the spinning frame for moving the motor relative to the drive shaft of the spinning frame, other means also driven by the machine for moving the two faces of the expansion pulley away from each other as the motor moves away from the drive shaft of the spinning frame and for moving the two faces of the expansion pulley towards each other as the motor moves 25 towards the drive shaft of the spinning frame, and a belt mounted on said pulleys.
16. In a machine having a main drive shaft and a motor having a shaft for driving the said drive shaft, the motor shaft and the drive shaft each having a V-pulley thereon, one of said V-pulleys being split transversely of its longitudinal axis and having its two portions slidably

keyed on one of the shafts, a belt mounted on the two pulleys, means driven by the machine for moving the motor towards and away from said drive shaft and other means for moving the two portions of the split V-pulley away from and towards each other in proportion to the movement of the motor to thereby maintain the desired tautness in the belt. 5

17. In a fiber preparation machine having a main drive shaft and a motor provided with a shaft and also having a vertically reciprocating ring rail, a V-pulley mounted on one of the shafts to rotate therewith, an expansion V-pulley having its two parts slidably keyed on the other of said two shafts to rotate therewith, a belt 10 mounted on said V-pulleys, means driven by the ring rail for moving said motor towards and away from said drive shaft, and other means driven by the ring rail for moving the two portions of the expansion V-pulley relative to each 15 other in proportion to the travel of the motor to thereby maintain a uniform tautness in the belt.

18. In a fiber preparation machine having a main drive shaft and a motor provided with a shaft and also having a vertically reciprocating ring rail, a V-pulley mounted on one of the shafts to rotate therewith, an expansion V-pulley mounted on the other shaft and having at least one of its two parts keyed for sliding movement 20 longitudinally of its shaft, a belt mounted on said V-pulleys, means driven by the ring rail for moving the motor towards and away from the main drive shaft, and other means driven by the ring rail for moving at least one of the two portions of the expansion V-pulley relative to the other portion in proportion to the travel of the motor to thereby maintain a uniform tautness in the belt. 25

19. In a fiber preparation machine having a main drive shaft and a reciprocating ring rail and a motor provided with a shaft, a V-pulley mounted on each of the shafts and a belt mounted on said pulleys, one of the pulleys being split and at least one portion thereof being keyed 30 for sliding movement along its shaft with relation to the other portion of the pulley, means for holding the split pulley in position for movement of the parts thereof relative to each other, means for moving the motor relative to the drive shaft, driving means driven by reciprocation of the ring rail for moving the means for moving the motor in one direction, means governed by the movement of the motor for rendering the driving means inoperative, other means for driving the means for moving the motor in the other direction, means for rendering the second driving means inoperative after a predetermined number 35 of revolutions of the motor have occurred after the first driving means have been rendered inoperative, the second driving means having a driving ratio to drive the means for moving the motor at a much greater rate of speed than the first driving means. 40

JAMES A. JEPSON. 65
